UNITED STATES PATENT OFFICE.

WILLIAM JAKOB BEISEL, OF BROOKLYN, NEW YORK.

NON-REFILLABLE BOTTLE.

1,144,286.

Specification of Letters Patent. Patented June 22, 1915.

Application filed July 16, 1914. Serial No. 851,382.

To all whom it may concern:

Be it known that I, WILLIAM JAKOB BEISEL, a citizen of the United States, residing at Brooklyn, county of Kings, State of New York, have invented certain new and useful Improvements in Non-Refillable Bottles, of which the following is a specification.

The present invention relates to improvements in non-refillable bottles and particularly to improvements and modifications 10 made in the structure for which I have heretofore obtained Letters Patent of the United States No. 1,079,387, dated November 25, 1913.

15 The improvements will be described in connection with the accompanying drawing, in which,

Figure 1 is a vertical sectional view through a bottle constructed in accordance 20 with the invention; Fig. 2 is a detail perspective view of one member of the device; Fig. 3 is a sectional view substantially on the line 3—3 of Fig. 2; Fig. 4 is a similar view on the line 4—4 of Fig. 2; and Fig. 5 25 is a detail of a slight modification.

Referring to the drawings, 1 designates the body of a bottle within the neck section 2 of which is suspended a cylinder 3. The cylinder 3 is provided at its upper or outer 30 end with an annular flange 4 which rests upon a ledge 5 in the bottle neck and said cylinder is of such cross sectional size that it is practically out of contact with the wall of the bottle neck throughout its length. Said cylinder is provided in its side wall 35 with a plurality of openings or liquid passages 6 and has an opening 7 in its inner wall for a purpose hereinafter more particularly referred to.

40 The bottle neck is formed of two sections, the one, 2, being integral with the body of the bottle and the outer section 8 being securely attached to said section 2, as by a collar 9 engaging suitable grooves in the neck sections.

Within the neck of the bottle beyond the outer end of the cylinder 3 is arranged a member 10 having at its inner end an annular flange 11 of substantially the diameter 45 of the opening at the outer end of the neck section 2; and this member 10 is provided with an interior tubular tapered valve seat within which is arranged a suitable valve. The valve shown has a hollow tapered body 55 12, adapted to fit closely within the tapered

valve seat and projecting slightly beyond the inner end of the member 10 into the cylinder 3. The outer end of the valve body 12 is closed by a cork 13 preferably secured in position by forming slightly inwardly 60 projecting ridges 14 on the body 12, said ridges having the form of an interrupted thread so that the body of the valve may be produced by a solid mold core, which can be released by merely giving it a slight 65 rotary movement.

At its inner end the valve is provided with a projection 15 having an eye to which is secured one end of a suitable flexible means 16, the other end of which is connected to 70 an eye at one end of a weight 17. The latter is similarly connected by a flexible means 18 with a support in the bottom of the bottle in substantial alinement with the projection 15 on the valve. In the form of the 75 invention shown in Fig. 1, this connection at the bottom of the bottle is by a screw-plug 19 having an inwardly projecting member 20 in which is formed an eye to receive the flexible connection 18. If desired, however, 80 as shown in Fig. 5, the bottom of the bottle may be provided with a suitable plug through which the flexible member 18 will extend and be secured against its outer surface.

85 As before pointed out, the flanges 4 and 11 are of substantially the same diameter and fit relatively close within the upper end of the neck section 2, the flange 11 being of such thickness that it projects beyond the 90 outer end of said neck section. To positively prevent any liquid from entering the bottle about said flange 11, as for example if a vacuum be created in the bottle and liquid admitted through the outer end of 95 the neck, it is preferred to interpose a thin disk-like sheet 21, of any suitable material, between the cylinder 4 and valve seat member 11, said sheet 21 extending as shown over the upper or outer surface of the neck 100 section 2. Preferably also the member 11 is provided on its inner or lower face with a slight annular rib, as shown. In the drawing, the thickness of said flexible washer-like member 21 is exaggerated in 105 order that it may be clearly shown. A washer 22 is provided about the projecting portion of the flange 11 and between the two sections or members of the bottle neck.

Within the outer portion or section 8 of 110

the neck of the bottle, beyond the valve seat member 10 is arranged a guard shown as comprising a body 23 which rests upon a washer 24 seated in a suitable recess at the 5 outer end of the member 10, said body having a central aperture 24 at its outer end over which is arranged a disk or guard piece 25 supported by members 26 so that a plurality of liquid outlets 27 is provided; and 10 at its outer end said member 23 has a series of spaced projections 28 which bear against a washer 29 interposed between them and the body of the bottle neck, thus providing fluid passages 30 communicating with the 15 aforesaid passages 27. At the extreme outer end of the neck of the bottle is arranged a cork 31.

The cylinder 3 is provided in the embodiment of the invention shown with two diametrically oppositely arranged longitudinal grooves which receive lugs or outwardly projecting ribs 32 on a tubular hammer 33. At their outer ends said grooves communicate with slots in the side wall of the cylinder, in which slots are arranged plugs provided with inwardly projecting flexible fingers 34 of any suitable material. As shown, these fingers are of such length that they extend across the path of the projections 35 at the outer end of the tubular hammer 33 and overlap the inner end of the valve 12. Normally, as shown in Fig. 1, the fingers 34 are out of contact with the inner end of the valve, but when the bottle is inverted and 35 the hammer 33 strikes said fingers they will be deflected sufficiently to transmit a slight blow to the inner end of the valve, which will move the same from its seat and permit liquid to flow from the body of the bottle through the neck. As soon as the force 40 of the blow referred to is exhausted said fingers 34 will impart a slight movement in the opposite direction to the hammer so that the fingers will offer no obstruction to movement of the valve in the opposite direction. The fingers 34, which may be of any suitable 45 material, therefore, constitute a means for protecting the inner end of the valve from damage that might result from direct contact with the hammer and also to maintain said parts in the proper relation when the valve is opened so that there is no possibility of the latter failing to close immediately if any attempt is made to force liquid into the 50 bottle through the neck thereof.

To cushion the movement of the hammer in the opposite direction, a washer 36 is arranged within the cylinder, being held from movement longitudinally thereof by lateral 60 projections 37 which enter openings 38 formed in the side wall of the cylinder at the inner end thereof. If desired, the cylinder may be provided adjacent its lower end with an inwardly extending annular rib

beneath which the washer 38 may be forced, 65 so that it is securely retained in place, instead of employing the lateral projections 37 as described.

The operation and advantages of the construction hereinbefore described will be 70 readily understood and appreciated. It will be seen that the weight 17 is so connected with the valve that it constitutes an automatically acting locking means by which the valve is held securely in its seat except 75 the bottle be inverted and the hammer caused to impart a slight blow to the inner end thereof. The particular construction of valve is important as it provides an extremely sensitive device which will be seated 80 on the slightest pressure from the outer end. It has been practically demonstrated that with the construction described a high vacuum may be created within the bottle and if, under such condition, liquid is admitted to the outer end of the neck the valve will seat itself and positively prevent the admission of a single drop to the interior of the bottle.

The cylinder, valve seat, body of the valve 90 and hammer are all preferably made from molded glass, although any material which will not be affected by the contents of the bottle can be employed.

Having thus described the invention, what 95 is claimed is:

1. The combination with a bottle having a neck, of a cylinder suspended in the neck of the bottle and provided in its side wall with a plurality of passages through which 100 liquid can flow from the body of the bottle, a tapered valve seat beyond the outer end of said cylinder, a tapered valve adapted to fit said seat and have its inner end project slightly into said cylinder, a weight within 105 the body of the bottle, means flexibly connecting the weight to the valve and a fixed support at the bottom of the bottle, and a sliding hammer supported by and within the cylinder and adapted to impart a slight 110 blow to the inner end of the valve when the bottle is inverted.

2. The combination with a bottle having a neck, of a cylinder suspended in the bottle and provided with a plurality of lateral 115 openings through which liquid from the body of the bottle can flow, a tapered valve seat arranged beyond the outer end of said cylinder, a tapered valve adapted to fit said seat and have its inner end project slightly 120 into the outer end of the cylinder, means for holding the valve in contact with the seat to prevent the flow of liquid through the bottle neck, a hammer supported to slide within the cylinder and adapted to impart 125 a slight blow to the valve to move it from its seat when the bottle is inverted, and a plurality of flexible fingers carried by the

cylinder and projecting into the path of the hammer adjacent the valve, for the purpose described.

3. The combination with a bottle having a neck, of a cylinder suspended in the bottle and having a plurality of lateral liquid passages extending through its side wall and a plurality of longitudinally extending grooves formed in its inner surface, a tapered valve seat arranged beyond the outer end of said cylinder, a tapered valve adapted to fit said seat and have its inner end project into the outer end of said cylinder, means for holding said valve in contact with the seat to prevent the flow of liquid through the bottle neck, and a tubular hammer having projections engaging the longitudinal grooves in said cylinder and adapted to impart a slight blow to the valve when the bottle is inverted.
4. The combination with a bottle having a neck, of a cylinder suspended in the bottle and having a plurality of lateral liquid passages extending through its side wall and a plurality of longitudinally extending grooves formed in its inner surface, a tapered valve seat arranged beyond the outer end of said cylinder, a tapered valve adapted to fit said seat and have its inner end project into the outer end of said cylinder, means for holding said valve in contact with the seat to prevent the flow of liquid through the bottle neck, plugs fitted in the outer ends of the longitudinal grooves of said cylinder and provided with inwardly projecting flex-

ible fingers which are normally out of contact with the inner end of the valve, and a tubular hammer adapted to slide in said longitudinal grooves in the cylinder and through said flexible fingers impart a slight blow to the inner end of the valve when the bottle is inverted.

5. The combination with a bottle having a neck, of a cylinder suspended in the neck of the bottle and extending into the body thereof, said cylinder having its side wall provided with a plurality of liquid passages and having longitudinally extending grooves formed in its inner surface, a tapered valve seat arranged beyond the end of said cylinder, a tapered valve adapted to fit said cylinder, a weight within the body of the bottle connected with the valve to hold the same in close contact with its seat unless the bottle is inverted, a hammer engaging said longitudinal grooves in the cylinder and adapted to impart a slight blow to the inner end of the valve when the bottle is inverted, a washer at the inner end of said cylinder for cushioning the blow of the hammer in that direction, and yielding means arranged between the hammer and the inner end of the valve for cushioning the blow of the hammer in that direction.

In testimony whereof I affix my signature in presence of two witnesses.

WILLIAM JAKOB BEISEL.
